TAPE PACKAGING MACHINE

Thomas Edison Westall, Marion, N.C., assignor to The American Thread Company, New York, N.Y., a corporation of New Jersey

Filed Jan. 26, 1960, Ser. No. 4,659

14 Claims. (Cl. 53—120)

This invention relates to machines suitable for use in packaging relatively thick tapes or ribbons and more particularly to machines suitable for packaging so-called Velcro tape.

Recently, there has been developed in the textile field a pair of tapes which adhere tenaciously one to the other. One of the two tapes is provided on one face with a myriad of hooks which extend in a substantially perpendicular direction from the face of the tape. The other of the two tapes is surfaced on one side with a large number of miniature loops. Pressing the looped surface of one tape against the hooked surface of the other tape results in a very strong bond between the two tapes. Sets of tapes of this type are presently being employed in various forms of garments to provide the means whereby the particular garment may be opened and closed taking the place, for example, of a zipper. Such tape is presently being fabricated and sold under the trademark Velcro.

In order to commercially distribute Velcro tape to the buying public, it is necessary to package it in a form which can be easily handled. A suitable package of the Velcro tape comprises two of the interengageable tapes assembled together face to face as a folded length of tape strip and bound by a strip of banding material bent around said folded tape strip.

Accordingly, the main object of the present invention is to furnish a means whereby Velcro tape may be suitably packaged.

A machine produced in accordance with the present invention measures the tape components of the Velcro tape each in a predetermined length and unites them face to face, cuts the tape components to form a united tape strip of such length, folds the cut strip approximately in half, measures a banding material in a predetermined length, cuts a strip of banding material of such length, and bands the folded Velcro tape strip with the strip of banding material, thus providing a Velcro tape package.

In general, the machine of this invention provides means for feeding and metering like lengths of a plurality of tapes and superposing them to form a multi-layer tape strip, means for cutting or severing the tape strip into a predetermined length, means for folding the cut tape strip, means for feeding and metering banding material, means for cutting or severing a predetermined length of the banding material and applying it to the folded tape strip and means for bending the cut length of banding material around the folded tape strip so as to embrace and package the latter.

The invention will be more readily understood when taken in conjunction with the following drawings, in which:

FIGURE 31 is a schematic drawing of the electrical and pneumatic connections associated with the machine of FIGURE 1, and

FIGURE 32 is a perspective view of a packaged Velcro tape strip produced by the machine of FIGURE 1.

With respect now more particularly to the drawings, a machine in accordance with this invention is shown in perspective in FIGURE 1. The rolls 175 and 176 of the two different Velcro tape components are mounted on a stand 177 so that each may rotate and release its tape component as required by the demands of the machine. With respect to roll 175, the tape 178 leaving

said roll is routed over stationary roller 179 and rotatable roller 180 mounted on spring-loaded arm 181. The tape 178 then passes beneath stationary roller 182 and thence into the machine. Using this type of feeding mechanism has been found to be desirable in view of the fact that the tape feed into the machine is intermittent.

Thus, when the machine calls for a certain length of tape, spring-loaded arm 181 moves in such a direction that the tape component 178 which is fed into the machine is that which was previously held between stationary rollers 179 and 182. The same type of feed as is described in connection with the tape component from roll 175 is embodied in feeding the Velcro tape component 183 from roll 176 into the machine. This means of feeding the tape components 178 and 183 prevents overrunning of rolls 175 and 176 and thereby avoids fouling of the tapes emanating therefrom.

As described above, the Velcro principle involves the use of two different types of tape components, one of which is equipped with a myriad of hooks, whereas the other is provided with a large number of loops. The tape components are fed into the machine from rolls 175 and 176 in such manner that the surfaces of the two tape components which are provided with the hooks and loops, respectively, are face to face. Thus, they become united in the machine to form a tape strip.

FIGURE 6 shows the manner in which the tape components are pulled from the rolls 175 and 176 and fed into the machine. Roller 10, constructed from or surfaced with a rubber-like material, rotates a predetermined number of revolutions as a result of being driven by an air cylinder piston, the driving linkage being described more fully below. Idler roll 11, also fabricated from or surfaced with a rubber-like material, is forced into frictional contact with driven roller 10 by proper adjustment of set screw 184. Thus, the initiation of the packaging process is the rotation of rollers 10 and 11 which unite the tape components 178 and 183, and feed a predetermined length of tape strip into the machine.

As the tape strip leaves rollers 10 and 11, it is fed through guide 17 which assures the tape strip remaining in the proper horizontal plane. The tape strip is also prevented from shifting from side to side by the shape of guide 17.

The next step in the operation of the inventive machine is the cutting of the united tape strip to form a tape strip of predetermined length. This is accomplished by the tape cutting assembly 18 shown in elevation in FIGURE 4. Cutting action is supplied by the scissors-like action of stationary knife edge 72 and movable knife edge 23. Air cylinder 19 is actuated in a manner to be described more fully below, thereby causing piston rod 20 to move in a downward direction. This motion is transmitted by link 21 which is pivotally connected to knife edge holder 22 which is pivoted about fixed point 24. In this manner, a predetermined length of the united tapes 178 and 183 is cut, resulting in the formation of tape strip 185.

The next succeeding step in the packaging operation consists of folding the cut tape strip 185 in half. Shown in FIGURE 7 is the portion of the machine which accomplishes this result. Folding blade 26 is caused to move in a downward direction, thereby making contact with the center of strip 185. As blade 26 continues to move in a downward direction, it depresses the center of tape strip 185 as shown in phantom in FIGURE 10. This portion of the machine, after completion of the folding step is shown in FIGURE 8.

When the folding step is completed, the movable jaw 32 of clamping jaw assembly 186 moves into the locked position as shown in FIGURE 8. Pins 34 together with pins 33 hold the folded strip 185 securely and prevent any movement during the following sequence of steps.

The second phase of the packaging operation involves appropriately positioning a strip of a banding material

5 of proper length, and subsequently bending the strip of banding material about the folded Velcro tape strip 185 so that the tape strip will remain folded after its release from the packaging machine. A source roll 187 of banding material 37 of aluminum strip of suitable gauge and width or other desirable metal is mounted so that it may feed banding material 37 as demanded by the packaging machine. FIGURE 2, a plan view of the packaging machine shows that the feed path of banding material 37 is at right angles to the direction of feed of the Velcro tape strip 185.

As shown in FIGURES 23, 24 and 25, banding material 37 is fed from roll 187 into guide 188. Banding material 37 is fed by the action of banding material feed assembly 189 which is described in detail below. Briefly, feeding of banding material 37 is accomplished by causing arm 118 to pivot about point 126 thereby causing projection 120 on head 119 to enter one of the spaced holes 133 (FIGURE 25) in banding material 37. Arm 118 and associated linkages are then caused to move toward the folded Velcro tape strip 185 and the interlocking of projection 120 and hole 133 causes banding material 37 to move along with arm 118. The length of travel of arm 118 is determined as described below and is made equal to the desired length of the strip of banding material 37 to be used in banding the folded Velcro tape strip 185.

The machine at this stage of its operation is shown in FIGURE 27. The next step consists of cutting banding material 37 and this is accomplished by the scissors action of knife edges 38 and 39. Prior to the cutting action of knife edges 38 and 39, ram head 42 which is attached to shaft 49 moves into contact with banding strip 37. This is best seen in FIGURE 24. Thus, following cutting of banding material 37, severed banding material strips 41 are held in place against the folded tape strip 185 by head 42 as shown in FIGURE 16.

The last steps in the packaging operation involve bending severed banding strip 41 appropriately about folded Velcro tape strip 185. This sequence of steps is shown in FIGURES 16, 17 and 18. The first step in this operation involves movement of head 45 which is attached to shaft 44 toward the folded tape strip 185. As shown in FIGURE 17, this causes the extremities of arms 43 to bend the banding strip 41 about the side edges of the folded Velcro tape strip 185. Next, beveled head 46 moves toward the Velcro tape strip 183, thereby bending strip 41 as shown in FIGURE 18 to embrace the strip 183. The last step involves pinching the banding strip 41 embracing the strip 185; this is accomplished by movement of head 45 away from the Velcro tape 185 while maintaining head 41 stationary, thereby causing the extremities of arms 43 to pull inward and effect pinching of the embracing band 41 about said strip.

By appropriate movement of head 45 and beveled head 46, the above-described sequence of movement is reversed and the band enfolded Velcro tape strip 51 as shown in FIGURE 32, is released and drops onto chute 52 and thence onto the conveyor belt 53 which transports it to a next succeeding operating point.

The motivation means or central timing mechanism for most of the moving parts of this machine is provided by a series of cams A-G inclusive mounted on cam shaft 62, shown in elevation in FIGURE 3 and plan in FIGURE 2. Cam shaft 62 is driven by a rotary power means 196 (FIGURE 1) such as a one-third horsepower gear head motor. The motor 196 is connected to cam shaft 62 through gears 199 and 198 and chain 197. Motor 196 also furnishes the power for conveyor belt 53 as shown in FIGURE 1.

The cams A-G employed in this machine are linked to rocker arms which are mounted on a rocker arm shaft 61, as shown in FIGURE 3. Rocker arm shaft 61 is supported by the base of the machine at its extremities

and is also braced by member 195 as shown in FIGURE 3.

FIGURES 3, 5 and 6 depict the operation of the tape feed mechanism. Air cylinder 16 is used to produce a predetermined amount of rotation of gear 13. This is accomplished by pivotally connecting piston rod 15 to a base of gear 13 at an eccentric point 193. When air pressure is applied to cylinder 16, in a manner to be described in connection with FIGURE 31, piston rod 15 enters the cylinder for a distance as determined by appropriate adjustment of cylinder 16 by adjustment means 200. The rectilinear movement of piston 15 is thus converted to a corresponding rotary movement of gear 13. Since point 193 travels in a curved path, platform 190 on which air cylinder 16 is mounted is pivoted about point 191 to permit the end of piston rod 15 to follow this curved path.

The rotary motion of gear 13 is transmitted to gear 12 with which it is meshed. Gear 12 is connected to the axle 201 of roller 10 through overrunning clutch assembly 202. Clutch assembly 202 is so connected that rotation of gear 12 in a direction which would tend to feed tape into the machine, a clockwise direction as viewed in FIGURE 3, causes a corresponding rotation of roller 10. Conversely, when gear 13 is driven reversely as a result of piston rod 15 moving out of cylinder 16 and returning to its normal position, which, in turn, causes gear 12 to move in a counterclockwise direction as seen in FIGURE 3, overrunning clutch assembly 202 causes roller 10 to be disengaged and permits gear 12 to rotate freely.

To prevent roller 10 from continuing to rotate in the feeding direction after gear 13 has completed its movement, brake assembly 194 (FIGURE 5) is employed. Any conventional brake assembly is suitable for this purpose, such, as, for example, a wheel attached to axle 201 which is provided with a spring-loaded belt appropriately disposed to prevent overrunning of roller 10.

The sizes of gears 12 and 13, the diameter of rollers 10 and 11, and the trance of piston rod 15 are appropriately chosen to feed a tape strip 185 of desired length into the machine.

Rollers 10 and 11 are grooved to prevent damage to the Velcro tape components being fed into the machine. As stated above, idler roller 11 is caused to rotate by forcing it into frictional engagement with driven roller 10 with set screw 184. It is necessary to groove rollers 10 and 11 to avoid excess pressure on the tape components since otherwise the pressure exerted against roller 10 by roller 11 would distort the Velcro tape strip.

The operation of tape strip cutting assembly 18 is actuated by the closing of microswitch 203 which is mounted on air cylinder 16 as shown in FIGURE 3. As piston rod 15 reaches the end of its travel into cylinder 16, adjustable member 204 mounted on piston rod 15 contacts microswitch 203 and causes it to close. Referring to FIGURE 4, the closing of microswitch 203 results in a downward movement of piston rod 20, thereby causing the Velcro tape strip to be cut. As indicated in FIGURE 4, the air cylinder 19 is pivoted about point 138 to permit the end of piston rod 20 to follow the cured path of knife edge holder 22 as the latter rotates about point 24. FIGURE 7 shows Velcro tape strip 185 just after it has been cut.

To assure the proper orientation of each Velcro tape as it is fed into the machine prior to the cutting step, guides 69, 71 and 72 are provided.

The action of a folding blade 26 is controlled by the rotation of cam B as shown in FIGURE 7. Cam follower assembly 55 is employed to produce the appropriate rectilinear motion based on the design of cam B. As shown in FIGURE 7, yoke 56 is mounted on cam shaft 62 in a manner which permits shaft 62 to rotate independently thereof. Cam follower wheel 54 is connected to member 58 through guides 63 and 64 which pass through holes

in the flanges of yoke 56. Cam follower wheel 54 is caused to follow the periphery of cam B by springs 57 mounted as shown in FIGURE 7.

Adjustable stud 204 is employed to limit the travel of the cam follower wheel on the low side of the cam B. This feature permits the travel of folding blade 26 to be adjusted without the necessity of replacing or reshaping cam B.

The direction of rotation of cam shaft 62 is counterclockwise, as viewed in the drawings. Counterclockwise movement of cam B as shown in FIGURE 7 results in movement of cam follower wheel 54 away from cam shaft 62. This in turn compresses springs 57 and causes member 58 to move in a downward direction. Adjustable link 59 which is connected to member 58 also moves in a downward direction. Rocker arm 60 which is rotatable about rocker arm shaft 61 is caused to rotate in a clockwise direction by the downward movement of link 59 to which it is pivotally connected. Link 65 which is pivotally attached to the other end of rocker arm 60 is thereby caused to move in a substantially horizontal direction. Link 66 which is rotatable about fixed point 70 is caused to move in a counterclockwise direction about this point by virtue of the motion of link 65 to which it is pivotally connected. The rotational movement of link 66 is transmitted to arm 28 through tension spring 67 and link 68. Arm 28 is pivoted about point 70 as shown in FIGURE 9 and accordingly moves in a counterclockwise direction.

As shown in FIGURE 10, folding blade 26 is linked to arm 28 by means of pin 30 and slot 29. As arm 28 moves in a counterclockwise direction about point 70, folding blade 26 is caused to move in a downward direction through guide 27. Since the path of folding blade 26, and accordingly, the path of pin 30 attached thereto, is rectilinear, slot 29 is provided to compensate for the fact that the end of arm 28 moves in a curved path.

Link 66, spring 67 and link 68 form the safety feature which protects the folding blade assembly. Thus, for example, if some circumstance precludes the downward movement of folding blade 26, the rotation of link 66 in a counterclockwise direction merely results in the expansion of tension spring 67. This safety feature thus prevents the positive action of cam B from being exerted by folding blade 26 against any foreign object which may be preventing its normal downward movement.

Clamping jaw assembly 186 is operated by means of cam F as shown in FIGURE 12. The clamping jaw assembly 186 has three basic positions. At the stage of operation depicted in FIGURE 12, the clamping jaw is moving toward the middle position. As cam F rotates in a counterclockwise direction, cam follower wheel 73 moves downward away from cam shaft 62 thereby causing member 76 which is attached to shafts 77 and 78 to move in a downward direction. Adjustable link 79 moves in a downward direction and causes rocker arm 80 which is pivotally attached thereto to rotate in a clockwise direction about rocker arm shaft 61. This movement of rocker arm 80 causes link 81 to move to the left. This movement in turn is transmitted through links 82, 83 and 88 to link 91. The movement to the left of link 91, which is pivotally connected to link 89, causes movable jaw 32 to rotate about pivot point 92 and thus move toward stationary jaw 31.

When cam F, as shown in FIGURE 12, is rotated so that the follower wheel 73 is riding on the highest point of the cam, jaws 32 and 31 assume the locked position. This situation is depicted in FIGURES 8 and 11. When the jaws are in the locked position, serrated edge 35, which is attached to the lower of pins 34 pinches the folded Velcro tape. This serrated edge is used to prevent upward movement of the folded tape which might otherwise occur as folding blade 26 moves upward out of contact with the folded Velcro strip 185.

A safety feature is included in the operation of clamping jaw assembly 186. As shown in FIGURE 12, link

88 is partially disposed inside of link 83. Compression spring 86, which is prevented from lateral movement by shoulder 87, is biased against link 83. The force of compression spring 86 maintains pin 84, which is connected to link 88, at the left-hand side of slot 85. So long as there is no obstacle to the free movement of movable jaw 32, pin 84 remains stationary at the left-hand side of slot 85; however, should movable jaw 32 be prevented from closing by the presence of a foreign body, for example, links 88 and 83 would telescope thereby compressing spring 86. Such telescoping effect is limited by the travel of pin 84 in slot 85. Thus, the travel of link 81 due to rotation of cam F may be absorbed by the compression of spring 86, thereby preventing any undesirable result should movable jaw 32 be unable to function properly.

Adjustable stud 74 which is attached to yoke 75 of cam F, is employed as described above to limit the travel of member 76.

The band feeding assembly 189 is actuated by rotation of cam A as shown in FIGURE 28. Yoke 96 is mounted on cam shaft 62 in a manner which permits the cam shaft 62 to rotate independently of the yoke. The movement of cam follower wheel 95 is transmitted by guides 97 and 98 to member 100 which is biased by springs 99. Counterclockwise movement of cam A, as shown in FIGURE 28, results in a downward movement of member 100. Adjustable link 101 also moves in a downward direction thereby causing rocker arm 102, which is pivotally connected thereto, to rotate in a clockwise direction about rocker arm shaft 61. Clockwise rotation of rocker arm 102 causes arm 112 to move to the left in a substantially horizontal direction. Of course, rotation of rocker arm also causes arm 112 to move in a vertical direction. Since, as will become apparent from the following description, arm 112 is also caused to move in a third direction, the left-hand end of arm 112 is attached to link 113, as shown in detail in FIGURE 26, by means of universal joint 205.

The sequence of movements resulting from the movement of arm 112 is described with reference to FIGURE 23. The movement of arm 112 to the left causes link 113, to which it is connected by universal joint 205, to move in a clockwise direction about fixed pivot point 137. Accordingly, link 115 which is pivotally attached to link 113 is caused to move in an upward direction. This in turn causes link 116 to move in a clockwise direction about fixed pivot point 136. The movement of the left-hand end of link 116 in an upward direction is transmitted to link 117 to which it is pivotally attached. Link 117 is connected to one end of arm 118. Arm 118 is rotatable about pin 126. Upward movement of link 117 results in clockwise rotation of arm 118 about point 126, until head 119 makes contact with banding material 37, as shown in FIGURE 24.

When head 119 makes contact with banding material 37, additional clockwise movement of link 116 about fixed pivot point 136 can no longer be absorbed by rotation of arm 118. Accordingly, such additional clockwise movement of link 116 results in movement of the entire banding material feed assembly 189 in an upward direction. This condition is shown in FIGURE 24.

FIGURE 25 depicts the banding feed mechanism at this stage of the operation. Supporting member 114 is connected to channel guides 128 and 129 which travel along track 127. Structural members 123 and 125 which support arm 118 and associated linkages are also connected to supporting member 114. Slot 130 is provided in guide 188 to permit head 119 to rest flush against banding material 37. Slot 130 is necessitated by projection 120 on head 119 which extends through one of holes 133 in banding material 37.

The travel of banding material feed assembly 189 along track 127 is made equal to the length of banding material

strip which is to be used to band the folded Velcro tape strip 185.

At this point in the operation, the banding material 37 is cut in a manner to be described in detail below. Continued rotation of cam A results in a reversal of the movements described above and return of the banding material feed assembly 189 to initial position, so that the banding material feed assembly 189 will be appropriately positioned and ready to feed banding material for the next banding operation.

Referring again to FIGURE 28, an upward movement of member 100 results in movement of arm 112 to the right. Referring to FIGURE 25, for ease of description, the above-described movement of arm 112 results in movement of link 116 in a counterclockwise direction about fixed pivot point 136. Due to the inertia of the system, particularly the friction of channel guides 128 and 129 on track 127, the first movement resulting from counterclockwise movement of link 116 is the rotation of arm 118 in a counterclockwise direction about pin 126. Continued counterclockwise movement of link 116 causes arm 118 to rotate about pin 126 until pin 124 comes to rest in slots 131 and 132. For this condition, further counterclockwise movement of link 116 cannot result in rotation of arm 118 and, therefore, the entire assembly 189 moves along track 127 in response to movement of link 116. Since the banding material feed assembly 189 is no longer locked in with banding material 37 through projection 120, movement along track 127 does not result in a corresponding retractive movement of banding material 37.

Brake assembly 134 is provided as shown in FIGURE 23 to prevent the banding material 37 from being dragged along by the return movement of banding material feed assembly 189. That is to say, brake assembly 134 permits free movement of banding material 37 in the feed direction but prevents movement in the reverse direction.

Banding material 37, after being fed as described above, is cut by the scissors action of knife edges 38 and 39 as shown in FIGURE 27. However, as stated above, ram head 42 must move into contact with the portion of banding strip 37 to be cut to hold the cut banding strip in place. Cam C and associated linkages, shown in FIGURE 19, actuate ram 42 and movable knife edge 38. Yoke 142 is attached to cam shaft 62 in the manner described above for the other cams. Cam follower wheel 139 transmits the peripheral motion of cam C to guides 140 and 141 which in turn are connected to member 297. Thus, in the position indicated in FIGURE 19, counterclockwise rotation of cam C results in a downward movement of member 297 and a corresponding downward movement of link 144. Rocker arm 145, which is pivotally attached to link 144, is caused to move in a clockwise direction about rocker arm shaft 61, thereby causing link 146 which is pivotally attached thereto, to move to the left. This motion of link 146 is transmitted to the top of link 147 to which it is pivotally attached. Link 147 is connected to shaft 158, and accordingly, movement of the top of link 147 to the left causes shaft 158 to rotate in a counterclockwise direction.

Shaft 158 rotates in a bearing, not shown, inserted in support member 208 as shown in FIGURE 14. Attached to shaft 158 is yoke 171 which is shown in plan in FIGURE 18, in front elevation in FIGURE 15 and in side elevation in FIGURE 14. Counterclockwise rotation of shaft 158 causes yoke 171 to move to the left. Shaft 49 is attached to assembly 168 which comprises guide 163. Guide 163 travels on shaft 161. As shown in FIGURE 18, guide 163 is attached to tension springs 209, the other end of springs 209 being connected to fixed support member 210. Thus, movement of yoke 171 to the left permits guide 163 and shaft 49 to move to the left a corresponding distance in response to the pull of spring 209. The travel of guide 163 is limited by stop nut 162. Thus, once guide 163 comes to rest

against stop nut 162, additional counterclockwise rotation of shaft 158 does not result in additional movement of shaft 49.

As shown in FIGURE 16, ram head 42 is attached to shaft 49. Accordingly, rotation of cam C as described above results in ram head 42 contacting banding material 37. As shown in FIGURE 16, folding blade 26 remains within folding Velcro strip 185. The travel of shaft 49 is adjusted so that the near side of folded Velcro tape 185 is compressed slightly against folding blade 26 by ram head 42. The machine at this stage of the operation is shown in perspective in FIGURE 27.

FIGURE 29 depicts the linkage which actuates movable knife edge 38 and causes banding material 37 to be cut. As described above, rotation of cam C causes shaft 158 to rotate in a counterclockwise direction. This causes link 103, welded to collar 213 which in turn is pinned to shaft 158, to move in a counterclockwise direction. Such motion of link 103 causes link 104, pivotally attached thereto, to move to the right. Accordingly, links 105 and 106 which are attached to link 104, also move to the right.

Knife edge 38 is rotatable about fixed point 94. The lower end of knife edge 38 is attached to pin 110 which is inserted in slot 211 in link 106. Pin 110 is positioned within slot 211 by adjustment of screw 111, floating shoulder 212 being biased against pin 110 by the pressure exerted by compression spring 106. The bias exerted by shoulder 212 prevents pin 110 from moving away from stud 111. Thus, counterclockwise rotation of shaft 158 causes pin 110 to move to the right, and this in turn causes the cutting surface of knife edge 38 to pass in sliding contact against knife edge 39, as shown in FIGURE 27. Thus, rotation of cam B produces both movement of ram head 42 and movement of knife edge 38.

As described briefly above, the next step in sequence is the forward movement of head 45 which causes arms 43 to bend banding strip 41 as shown in FIGURE 17. Head 45 moves as a result of movement of shaft 44 to which it is connected. Referring to FIGURE 14, it is seen that shaft 44 will move in response to the pull of tension springs 214 when yoke 170 moves to the left. Yoke 170 is attached to shaft 156 and moves when shaft 156 rotates. The linkage between shaft 156 and cam D is shown in FIGURE 20. The linkage is essentially that described in connection with cam C above with the exception that adjustable stud 215 is employed to limit the travel of cam follower wheel 216 on the low side of cam D. Stop nut 160 limits the movement of guide 164, which is attached to shaft 44 as part of assembly 167. Guide 164 travels on shaft 221. Accordingly, the travel of shaft 44 is limited by stop nut 160.

Movement of beveled head 46 causes bending of strip 41 as shown in FIGURE 18. As shown in FIGURE 17, arms 43 are pivoted about point 216 and are normally biased by compression springs 217 to the extent permitted by studs 218. Forward movement of beveled head 46 into contact with adjustable studs 219 causes arms 43 to move toward each other, thereby compressing springs 217.

Beveled head 46 is attached to shaft 47 which in turn is attached to assembly 166 as shown in FIGURE 14. Guide 165 which travels on shaft 222 and stop nut 159 act to limit the travel of shaft 47 as described above in connection with shafts 44 and 49. Yoke 169 is attached to shaft 157. Thus, rotation of shaft 157 permits tension springs 220 to control the travel of shaft 47. Shaft 157 is linked to cam E in the manner shown in FIGURE 21.

After completion of the banding step, further rotation of cams C, D and E results in the movement of arms 43 and shafts 49, 47 and 44 in a sequence of steps which is the reverse of that previously recited.

It is seen from the drawings that shafts 49, 44 and 47 telescope one into the other in accordance with movement

of cams C, D and E. Accordingly, shaft 44, the middle of the three shafts, is preferably constructed of brass or other bearing material to facilitate ease of movement between the shafts.

FIGURE 31 is a schematic drawing of the electrical and pneumatic connections which control the operation of air cylinders 16 and 19. The rotation of cam G, which is attached to cam shaft 62, controls the operation of the air cylinders. As shown in the drawings, microswitch 223 is in the closed position as a result of contact by the periphery of cam G. The closing of microswitch 223 energizes the solenoid 225. This in turn actuates four-way valve 226 in such manner that the left-hand portion of air cylinder 16 is connected to a positive pressure air supply and the right-hand portion of cylinder 16, on the other side of the piston, is connected to exhaust. This, of course, results in piston rod 15 moving into air cylinder 16.

Continued movement of piston rod 15 into air cylinder 16 ultimately results in closing of microswitch 203. This in turn energizes solenoid 224 and results in four-way valve 227 being disposed so that the top portion of cylinder 19 is connected to the air supply and the bottom portion is connected to exhaust. As a result of the pressure differences within cylinder 19, piston rod 20 is caused to move into cylinder 19. As described above, such movement of piston rod 20 results in knife edge 23 cutting the Velcro tape strip 185.

Continued counterclockwise rotation of cam G eventually results in the opening of microswitch 223 which is spring-loaded and the sequence of steps described above is reversed. Thus, piston rod 20 moves out of cylinder 19 and piston rod 15 also emerges from cylinder 16.

It is believed that the foregoing description is a sufficient foundation for a thorough appreciation of the cam diagram depicted in FIGURE 30. In essence, the operation of the machine is initiated at the point indicated by the 240° line in FIGURE 30. At this point, cam G makes contact with microswitch 223. Contact is maintained between cam G and microswitch 223 from the 240° point to the 360° point. During this time, a predetermined length of Velcro tape strip is fed into the machine. As described above in connection with FIGURE 31, the rotation of cam G ultimately results in cutting the Velcro tape strip 185.

Referring now to the 0° point, further rotation of cam A causes a predetermined length of banding material to be fed into the machine. This continues from the 0° point to the 60° point.

At the 15° point, further rotation of cam F causes the movable jaw 32 of clamping jaw assembly 186 to move forward into the middle position. This step continues from the 15° point to the 60° point.

At the 30° point, further rotation of cam B causes folding blade 26 to move downward into contact with the cut Velcro tape strip 185. This downward movement of folding blade 26 continues from the 30° point to the 90° point at which time the folding operation is completed.

At the 90° point, ram 42, actuated by rotation of cam C, moves forward to contact the banding material which has been fed into the machine. The banding material is also cut by the rotation of cam C.

At the 105° point, the movable jaw 32 of clamping jaw assembly 186 moves into the locked position as a result of rotation of cam F. This step is completed at the 120° point as shown in FIGURE 30.

Continued rotation of cam D at the 105° point causes head 45 to move forward. This in turn causes bending of the cut banding material strip by arms 43 as a result of the forward movement of head 45. This step continues until the 135° point.

The banding material feed assembly begins to return to its normal position at 105°. The return movement is completed at the 165° point as shown by reference to cam A in FIGURE 30.

At the 135° point, rotation of cam E causes beveled

head 46 to begin its forward movement. This results in the pivoting of arms 43 and the resulting bending of the banding material strip. This operation continues until the 180° point.

The pinching step is accomplished by the backward movement of head 45 which commences at the 180° point as shown by the line representing cam D in FIGURE 30. This operation continues until the 195° point.

Also commencing at the 180° point is the backward movement of ram head 42 which is actuated by the rotation of cam C. This operation also is completed at the 195° point.

At the 195° point, the folding blade 26 moves up from between the folded Velcro tape strip 185 as a result of rotation of cam B. This step continues from the 195° point to the 255° point.

Continued rotation of cam E at the 195° point causes beveled head 46 to move backward thereby permitting arms 43 to open. This step terminates at the 240° point.

Head 45 moves backward away from the banded Velcro tape strip as a result of rotation of cam D beyond the 240° point. The movement of head 45 is completed at the 270° point.

The final step in the production of a banded Velcro tape strip 51 is the opening of clamping jaw assembly 186 which commences at the 285° point as a result of the rotation of cam F. Movable jaw 32 moves to the open position, this step being completed at the 330° point, and the banded strip falls onto the conveyor 53.

It is to be understood that construction of a machine similar to that described above involves the customary procedures with respect to adjustment of cams and cam followers, and also adjustment of various linkages. Thus, for example, in many instances in the drawings linkages and shafts are indicated as including threaded portions which facilitate proper adjustment of travel or stroke of the particular machine parts.

It is to be appreciated that the machine depicted in the drawings is intended merely as illustrative of the present invention and variations such as the substitution of equivalent parts may be made by one skilled in the art within the scope of the appended claims without departing from the spirit and scope of this invention.

What is claimed is:

1. A machine for packaging tape strips embodying multiple superposed tapes comprising means for feeding and metering like lengths of the tapes and effecting their superposition, means for severing a predetermined length of the superposed tape to provide a strip, the ends of said strip after cutting being approximately equidistant from a first position, means disposed at said first position for folding the strip, a source of banding material, means for feeding and metering a length of banding material for application to the folded strip, the midpoint of said length of banding material being approximately coincidental with said first position, means for severing said length of banding material, and means located at said first position for bending the severed length of banding material around the folded strip to effect its packaging.

2. A machine for packaging tape strips embodying tapes having sets of interengageable components on adjacent faces comprising a first metering means for feeding predetermined like lengths of the tapes with each set of such components and effecting interengagement of said sets of components to provide a united tape, a first cutting means operable to sever a metered length of the united tape to form a strip, the ends of said strip being approximately equidistant from a first position, folding means disposed at said first position and operable on the said strip to fold it approximately in half, a source of banding material, a second metering means operable to feed a predetermined length of banding material for application to the folded strip, the midpoint of said length of banding material being approximately coincidental with said first position, a second cutting means operable to sever the

predetermined length of said banding material from its source, and bending means operable at said first position to bend the severed length of banding material around the said folded strip whereby the latter is packaged.

3. A machine for packaging tape strips embodying multiple superposed tapes comprising a first rotary cam, pneumatically operable means responsive to rotation of said cam for feeding and metering like lengths of the tapes and effecting their superposition, pneumatically operable severing means responsive to operation of said first-named means for severing a predetermined length of the superposed tape to form a strip, a second rotary cam, means responsive to rotation of said second cam for effecting folding of said strip, a third rotary cam, gripping means responsive to rotation of said third cam for holding the folded strip at a fixed position, a fourth rotary cam, a source of banding material, feeding and metering means responsive to rotation of said fourth cam for applying a length of banding material against the folded strip at said fixed position, a fifth rotary cam, a second severing means responsive to rotation of said fifth cam for severing a predetermined length of banding material from its source at said position, head means also responsive to rotation of said fifth cam for holding the severed length of banding material applied against said folded strip, a sixth and seventh rotary cams, bending means responsive to rotation of said sixth and seventh cams to bend said severed length of banding material around said folded strip to effect its packaging, and central timing mechanism for all said cams including a rotary cam shaft on which all of said cams are attached for rotation therewith and means for rotating said cam shaft.

4. A machine for packaging tape strips embodying a pair of differing interengageable tapes comprising a first metering means for feeding like lengths of the pair of tapes and effecting their interengagement to provide a united tape, a first cutting means operable to sever a metered length of the united tape to form a strip, the ends of said strip after cutting being approximately equidistant from a first position, folding means disposed at said first position, operable on the strip to effect its folding, a source of banding material, a second metering means operable to feed a predetermined length of the banding material for application to the folded strip, the midpoint of said length of banding material being approximately coincidental with said first position, a second cutting means operable to sever the predetermined length of banding material from its source, bending means operable at said first position to bend the severed length of banding material around the folded strip whereby the latter is packaged, and a central timing mechanism to which each of said first metering means, said folding means, said second metering means, said second cutting means and said bending means is responsive to effect its respective timely operations.

5. A machine for packaging tape strips embodying a pair of differing interengageable tapes comprising a first metering means for feeding like lengths of the pair of tapes and effecting their interengagement to provide a united tape, a first cutting means responsive to said first-named means and operable on the united tape to sever a metered length thereof to form a strip upon completion of metering by said first-named means, the ends of said strip after cutting being approximately equidistant from a first position, folding means disposed at said first position and operable on the strip to effect its folding, a source of banding material, a second metering means operable to feed a predetermined length of the banding material for application to the folded strip, the midpoint of said length of banding material being approximately coincidental with said first position, a second cutting means operable to sever the predetermined length of banding material from its source, bending means operable at said first position to bend the severed length of banding material around the folded strip whereby the

latter is packaged, and central timing mechanism for effecting timely operations of all said means.

6. A machine for packaging tape strips embodying a pair of differing interengageable tapes comprising a first metering means for feeding like lengths of the pair of tapes and effecting their interengagement to provide a united tape, a first cutting means responsive to said first-named means and operable on the united tape to sever a metered length thereof to form a strip upon completion of metering by said first-named means, the ends of said strip after cutting being approximately equidistant from a first position, folding means disposed at said first position and operable on the strip to effect its folding, a source of banding material, a second metering means operable to feed a predetermined length of the banding material for application to the folded strip, the midpoint of said length of banding material being approximately coincidental with said first position, a second cutting means operable to sever a predetermined length of banding material from its source, bending means operable at said first position to bend the severed length of banding material around the folded strip whereby the latter is packaged, and central timing mechanism for effecting timely operations of all said means, said mechanism comprising a cam shaft and a plurality of cams attached thereto and rotatable therewith.

7. A machine for packaging tape strips embodying a pair of differing interengageable tapes comprising a first metering means for feeding like lengths of the pair of tapes and effecting their interengagement to provide a united tape, a first cutting means operable to sever a metered length of the united tape to form a strip, the ends of said strip being approximately equidistant from a first position, folding means disposed at said first position and operable on the strip to effect its folding, a source of banding material, a second metering means operable to feed a predetermined length of the banding material in a direction transverse to the direction of feed of the pair of tapes for application to the folded strip, the midpoint of said length of banding material being approximately coincidental with said first position, a second cutting means operable to sever a predetermined length of banding material from its source at said position and bending means operable at said first position to bend the severed length of banding material around the folded strip whereby the latter is packaged.

8. A machine for packaging tape strips embodying a pair of differing interengageable tapes comprising means for feeding and metering like lengths of the pair of tapes and effecting their interengagement to provide a united tape, said means including a pair of frictionally engaged resilient rollers rotatable about their respective longitudinal axes and mounted one above the other so that the said axes are equidistant and also lie within a substantially vertical plane, said pair of tapes being passed and pressed together between said rollers, a reciprocally movable piston-containing air cylinder, cam means for operating the piston, a first gear pivotally connected to the piston, the connection to said gear being on a face thereof at a point removed from the center, a second gear meshing with the first gear and connected to drive the lower of said pair of rollers whereby rectilinear movement of said piston in the air cylinder is converted to rotary movement of said pair of rollers and the pair of tapes passed between them are fed and united, means for severing a metered length of the fed tape to form a strip, means for folding the strip and means for applying a length of banding material to the folded strip and bending it around the latter to effect its packaging.

9. A machine for packaging tape strips embodying a pair of differing interengageable tapes comprising means for feeding and metering like lengths of the pair of tapes and effecting their interengagement to provide a united tape, a first cutting means operable to sever a metered length of the united tape to form a strip, folding means

operable on the strip to effect its folding, means for applying a length of banding material to the folded strip, and means for bending said length of banding material around said folded strip to effect its packaging, said bending means including a rotary cam, a first head movable rectilinearly in response to rotation of said cam, a pair of spring biased substantially L-shaped arms pivotally mounted on said head, a second rotary cam, and a second head movable rectilinearly in response to rotation of said second cam and toward and away from engagement with said first head, said second head being adapted to effect pivotal movement of said arms on said first head toward each other when moved into engagement therewith.

10. A machine for packaging tape strips embodying a pair of differing interengageable tapes comprising means for feeding and metering like lengths of the pair of tapes and effecting their interengagement to provide a united tape, a first cutting means operable to sever a metered length of the united tape to form a strip, folding means operable on the strip to effect its folding, means for applying a length of banding material against the folded strip, the midpoint of said length of banding material being approximately coincidental with said first position, a first rotary cam, a first head movable in response to rotation of said first cam for maintaining the length of banding material against said folded strip, and means for bending said so maintained length of banding material around said folded strip to effect its packaging, said bending means including a second rotary cam, a second head movable rectilinearly in response to rotation of said second cam, a pair of spring biased substantially L-shaped arms pivotally mounted on said second head, a third rotary cam, a third head movable rectilinearly in response to rotation of said third cam and toward and away from engagement with said second head, said third head being adapted to effect pivotal movement of said arms on said second head toward each other when moved into engagement therewith.

11. A machine for packaging tape strips embodying a pair of differing interengageable tapes comprising means for feeding and metering like lengths of the pair of tapes and effecting their interengagement to provide a united tape, said means including a pair of rollers between which said pair of tapes is passed, said rollers being mounted one above the other so that their respective longitudinal axes are equidistant, a reciprocally movable piston-containing air cylinder, cam means for operating the air cylinder, a first gear pivotally connected to the piston, the connection to said gear being at an eccentric position on a face thereof, a second gear meshing with said first gear, a clutch assembly means between said second gear and the lower one of the rollers to permit driven rotation of the latter only in one direction when rectilinear movement of said piston in said cylinder effects rotary movement of said first gear whereby the pair of tapes passing between the rollers is fed, brake means connected to said lower one of said rollers to prevent its rotation except when it is driven by said second gear through said clutch assembly means, means for severing a metered length of the united tape so fed to form a strip, means for folding the strip, and means for applying a length of banding material to the folded strip and bending it around the latter to effect its packaging.

12. A machine for packaging tape strips embodying a pair of differing interengageable tapes comprising means for feeding and metering like lengths of the pair of tapes and effecting their interengagement to provide a united tape, a first stationary knife edge and a first pivotally mounted knife edge between which said united tape is passed, a first pneumatic means for pivoting said second-named knife edge against said stationary knife edge to sever a metered length of the united tape to form a strip, the ends of said strip being approximately equidistant from a first position, timing means operable by a second pneumatic means to control operation of the said first pneumatic means, folding means disposed at said first position and operable on the strip to effect its folding

and means for applying a length of banding material to the folded strip at said first position and bending it around the latter to effect its packaging.

13. A machine for packaging tape strips embodying a pair of differing interengageable tapes comprising a first metering means for feeding like lengths of the pair of tapes and effecting their interengagement to provide a united tape, a first cutting means operable to sever a metered length of the united tape to form a strip, folding means operable on the strip to effect its folding, a source of banding material, a second metering means operable to feed a predetermined length of the banding material to a position for application to the folded strip, rotary cam means, head means operated by rotation of said first cam means for application and maintenance of the banding material against said folded tape strip at said position, a first stationary knife edge, a second pivotally mounted knife edge, said banding material being passed between said edges, said rotary cam means also operable to pivotally move said second knife edge so as to sever said predetermined length of banding material from its source, movement of said head and said second knife edge being coordinated so that severing action of said second knife edge occurs at the same time or subsequent to the applica-

tion of said head means against the banding material, and means for bending the severed length of banding material around the folded strip to effect its packaging.

14. A machine for packaging tape strips comprising means for feeding and metering tape, means for severing a predetermined length of said tape to provide a strip, the ends of said strip being approximately equidistant from a first position, means disposed at said position for folding the strip, a source of banding material, means for feeding and metering a length of banding material for application to the folded strip, the midpoint of said length of banding material being approximately coincidental with said first position, means for severing said length of banding material, and means disposed at said position for bending the severed length of banding material around the folded strip to effect its packaging.
